TREATMENT OF FATTY ACIDS

Frank G. Amthor, East Rutherford, and George Zinzalian, Boonton, N. J., assignors to Wecoline Products, Inc., Boonton, N. J., a corporation of New Jersey

No Drawing. Application October 3, 1935,
Serial No. 43,300

7 Claims. (Cl. 23—250)

This invention relates to the higher fatty acids, and more particularly to the treatment thereof whereby discoloration of such compounds on standing is substantially prevented.

5 Higher fatty acids of both drying and non-drying types are in considerable demand for various uses. In some such uses, as for example, in the manufacture of alkyd resins, which are combinations of phthalic anhydride, glycerine 10 and higher fatty acids, the demand is becoming increasingly one for the lightest possible color in the fatty acids. One of the reasons for such a demand is that it is desired to make the resins of the lightest possible color and this necessitates 15 correspondingly light colored raw materials. Various attempts to produce light colored higher fatty acids have been made, and it is now standard practice to distill such acids under conditions whereby the resulting product is light colored. 20 However, the distilled fatty acids do not retain their color and they gradually darken on ageing. The cause of the darkening has not been definitely established, although it is suspected by some that oxidation plays some part 25 in the discoloration and, also, that some polymerization or even decomposition may take place. It is the view of some that impurities either naturally contained in the fatty acids or introduced by contamination may be a cause of or an influence 30 in discoloration. However, none of these views have been fully corroborated at the present time, and the cause of the discoloration may be said to be unknown.

The invention described herein is intended to 35 overcome the difficulties previously experienced in the discoloration of the fatty acids, it being among the objects thereof to provide a light colored fatty acid composition which is substantially stable in the presence of light and air, and which does not materially discolor after standing 40 for long periods of time or under the influence of heat.

The present invention is based upon a discovery made as the result of a considerable amount 45 of experimentation with substances of widely varied chemical and physical character, that if one adds to fatty acids a small amount of oxalic acid in suitable proportions and under certain conditions, discoloration of distilled fatty acids 50 is practically prevented. This preservation is not temporary, but continues over a long period of time and even under severe conditions.

Fatty acids thus stabilized against color change by oxalic acid have been heated according to a standard test, to 235° C. for five hours in

an atmosphere of nitrogen, which is extremely severe. Untreated fatty acids darkened very considerably when so heated, whereas fatty acids treated in accordance with the present invention remained of the same light color at the end of the test that they had at the beginning. In other words, fatty acids treated in accordance with the present invention remained practically unchanged in color.

The amount of oxalic acid which should be 10 used to give the results desired according to the present invention, is very small. It has been found that when one part of oxalic acid to 100 parts of fatty acids is used, the results are not at all beneficial. The fatty acids so treated 15 darken on ageing, on heat and on exposure to air and light, to even a greater degree than an untreated fatty acid. However, if one uses 1 part of oxalic acid to more than 1000 parts of fatty acid, that is, less than 0.1% of oxalic acid, preservation of the color is obtained. Reducing the 20 amount of oxalic acid used increases the extent of the preservation obtained up to a maximum, after which the effect decreases to that when 1 part of oxalic acid is used with 20,000 parts of fatty acids, the beneficial effect is still noticeable, but in further decreasing the proportion 25 of oxalic acid, the effect becomes negligible. Specifically, we have found that the best results are obtained when there is used 1 part of oxalic acid to 5,000—10,000 parts of fatty acids; that is, when the amount of oxalic acid in the final composition is from 0.02% to 0.01%.

We have also found that when, in conjunction 35 with the oxalic acid, a small amount of water is introduced in the fatty acids, the beneficial effects are improved. We, therefore, prefer usually to use oxalic acid in the crystalline state having two molecules of water of crystallization 40 therein. In some cases, more than the two molecules of water may be introduced into the composition, but if too much water is used it tends to render the fatty acids somewhat cloudy, and this is ordinarily to be avoided.

It is also desirable that distilled fatty acids to 45 be treated should not be allowed to come in contact with air between the distillation operation and the treatment. On a large scale, the treatment may very conveniently be performed by passing the liquid fatty acids substantially continuously as they are being condensed, through a 50 body of oxalic acid crystals and without allowing contact of the same with air, whereby solution of a very small amount of oxalic acid in the fatty acids takes place. The speed with which 55

- the fatty acids pass through the oxalic acid or the depth of the body crystals, or both, may be varied in order to give the desired amount of oxalic acid in the fatty acids. However, it is usually 5
 8 more convenient to by-pass a portion of the fatty acids through the oxalic acid crystals in order that a saturated solution of oxalic acid in the fatty acids may be obtained. Then, the treated fatty acids may be combined in the desired proportions with untreated fatty acids to give close 10
 10 control over the final proportions of the ingredients of the composition.

Fatty acids thus treated retain their natural color under a wide variety of adverse conditions 15 and the product itself is usable for all the purposes for which the untreated fatty acids are adaptable. The amount of oxalic acid present is so small as to be substantially negligible for all uses, and, furthermore, if the fatty acids are to 20
 20 be heated, as in chemical processes, the oxalic acid will decompose to H_2O , CO , and CO_2 , which will pass out of the reaction vessel leaving behind fatty acids practically free from oxalic acid.

The present invention is particularly desirable 25 for use in connection with unsaturated fatty acids, more specially such acids as are ordinarily considered to be of the drying type, such as linseed, soya bean and China wood oil fatty acids. However, equally good results are obtained in 30
 30 treating other fatty acids, such as oleic, stearic, cotton seed oil, fish oil, perilla oil, castor oil fatty acids, or the fatty acids of mixed vegetable oils.

We are aware that it had previously been proposed to treat certain organic compositions with 35 oxalic or other acids. For example, alkali earth metal compounds of certain organic acids present in turpentine or the like, such as calcium abietate, have been stated to act during distillation of turpentine as accelerators of oxidation and also to form complex compounds with other constituents of the turpentine, all of which rendered the subsequently distilled turpentine dark colored. It was, therefore, proposed to add oxalic acid to the turpentine for the purpose of reacting with the alkali earth metal and to precipitate an insoluble oxalate thereof, which was removed by filtration. This procedure is entirely different from the present invention, both in that 40
 40 the oxalic acid remains dissolved in the fatty acids and does not function as a precipitant, and we utilize the same to prevent discoloration in a distilled product, whereas the prior process utilizes a treatment prior to distillation.

It has also been proposed to use various organic compounds including oxalic acid or oxalates, in the treatment of compositions used in making coated fabrics. The composition is generally one of nitrocellulose containing a softener such as 45
 45 castor oil, and a solvent with which the fabric is impregnated, and the fabric is then dried. One of the difficulties encountered was in preventing the coated fabric on ageing from becoming sticky and eventually becoming brittle. To prevent this, it was proposed to add oxalic acid or salts in substantial amounts to the composition in order to maintain the coated fabric in its initial pliable state. Our invention has not relation to such a process and does not introduce oxalic acid for the purpose of maintaining pliability of the composition, but to prevent discoloration of fatty acids. 50
 70

It is also well known that fats on standing develop rancidity due either to oxidation or the action of enzymes formed by fungi, resulting in the development of objectionable odor and taste in the fats. To prevent this, it has been proposed to 5
 5 add to the fats, anti-oxidants of varied character, usually aromatic amines, organic nitro derivatives, phenols and the like. However, such compounds are of no substantial value for preservation of color in fatty acids. 10

Although we have described our invention setting forth several variations in the treatment to obtain the desired results, it is understood that variations, such as will become apparent to those skilled in the art, may be made in the details 15 within the scope of the invention. It may be possible to use other compounds in place of oxalic acids, as, for example, it has been found that a concentrated water solution of calcium hypochlorite also gives definitely favorable results. In 20 the treatment of varying types of fatty acids, it is found that somewhat different amounts of oxalic acid are required to give optimum results, and therefore the present invention contemplates variations in the amounts to be used, although in 25 all cases the optimum amounts fall within the limits set forth above. In the claims appended hereto, the term "higher fatty acids" is intended to include not only mixtures of fatty acids, but also individual and substantially pure fatty 30 acids, as well as distilled or crude fatty acids. These and other changes may be made in our invention, the scope of which is defined in the claims appended hereto.

What we claim is:

1. A method of treating higher fatty acids which comprises adding thereto a small amount of oxalic acid, whereby discoloration of said fatty acids is substantially prevented, the ratio of oxalic to fatty acids being 1 to 1,000-20,000. 35

2. A method of treating higher fatty acids which comprises adding thereto a small amount of oxalic acid, whereby discoloration of said fatty acids is substantially prevented, the ratio of oxalic to fatty acids being 1 to 5,000-10,000. 40

3. A method of treating higher fatty acids which comprises adding thereto a small amount of oxalic acid containing water, said amount being sufficient to stabilize said fatty acid against color change, the amount of water being insufficient to cause turbidity in the product, whereby discoloration of said fatty acids is substantially prevented, the ratio of oxalic to fatty acids being 1 to 1,000-20,000. 50

4. A method of treating higher fatty acids which comprises adding thereto a small amount of oxalic acid containing water, the amount of water being insufficient to cause turbidity in the product, whereby discoloration of said fatty acids is substantially prevented, the ratio of oxalic to fatty acids being 1 to 5,000-10,000. 55

5. A composition consisting of higher fatty acids containing a small amount of oxalic acid from 0.1% to 0.005%.

6. A composition consisting of higher fatty acids containing a small amount of oxalic acid from 0.02% to 0.01%. 65

7. A composition consisting of distilled linseed oil fatty acids containing an amount of oxalic acid from 0.02% to 0.01%.
